(57) **CLAIM**

The ornamental design for a cup, as shown.

DESCRIPTION

FIG. 1 is a perspective view of a cup showing my new design;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof; and,

FIG. 8 is another perspective view thereof with the upper part rotated.
The broken lines shown in FIGS. 1-2 and 4-8 are for the purpose of illustrating portions of the cup only and form no part of the claimed design.

1 Claim, 8 Drawing Sheets
